SHEET FOLDING MECHANISM

Robert C. Flynt, Winston-Salem, N. C., assignor
of two-fifths to Forrest G. Miles, Winston-
Salem, N. C.

Application July 20, 1934, Serial No. 736,239

12 Claims. (Cl. 270—68)

This invention relates to sheet folding mechanism and more particularly to sheet folding mechanism especially adapted for the folding of letters, circulars, advertising matter and the like, 5 although mechanism or apparatus according to my invention can be employed for other folding operations.

An object of the invention is to provide a mechanism of the character referred to which is of 10 simple, compact and inexpensive construction, being adapted more especially for use in the handling of folding operations of comparatively small volume, that is, of such volume that hand folding would be uneconomical, but not sufficiently large 15 to warrant the expense of the larger and more elaborate mechanism heretofore available. In attaining this object I provide a novel structure embodying folding elements, a feeding element and means cooperating with the feeding element 20 for maintaining sheets in such position relative to the frame as to render possible the compact arrangement of the various parts of the apparatus and at the same time assuring efficient and rapid operation.

25 A further object is to provide a folding mechanism of the kind referred to and which is adapted to form two parallel folds in a sheet either in a manner to fold both end portions towards the same face of the central portion of the sheet as 30 is customarily done with ordinary letters, or in such a way as to fold one end portion towards one face of the central portion and the other end portion towards the other face of the central portion so as to adapt the folded sheet, for example a letter, for use in connection with window envelopes. This may be accomplished, in 35 accordance with the invention, by the provision of means for selectively feeding one or the other end portions of the sheet to the folding elements 40 for the formation of the first fold, and means for controlling the operation of the folding elements in the formation of the second fold.

Another object is to provide a sheet folding apparatus of the type including buckling rolls and 45 a feed roller with driving and timing mechanism which provides for the passage of sheets through the folding rolls unhindered by the feed roller, the latter, however, being adapted to engage the next sheet of the pile as soon as the sheet being 50 folded is withdrawn from engagement with the feed roller, whereby successive sheets on the pile will follow each other through the folding rolls closely but separately and without danger of being folded together. In attaining this object, I 55 prefer to provide a feed roller in constant engage-

ment with the pile of sheets, and an over running drive device for the feed roller which permits the latter to free-wheel when the sheet which it engages is being drawn through the folding rolls.

Other objects will become apparent from a reading of the following detail description, the appended claims and the accompanying drawings, in which:

Figure 1 is a perspective view of the sheet folding mechanism embodying my invention;

Figure 2 is a sectional view taken on the line 2—2 of Figure 3, some parts being shown in elevation;

Figure 3 is a sectional view taken on the line 3—3 of Figure 2;

Figure 4 is a sectional view taken on the line 4—4 of Figure 2;

Figure 5 is a detail sectional view taken on the line 5—5 of Figure 3 and drawn on an enlarged 20 scale;

Figures 6 to 11 inclusive are diagrammatic views of folding rolls, a feed roller, and a sheet guide in position for forming a single fold, and graphically illustrating the operation and effect 25 of an over running drive for the feed roller;

Figures 12, 13 and 14 are diagrammatic views similar to Figures 6 to 11 but showing the sheet guide so positioned as to effect formation of two parallel folds in each sheet, the end portions of 30 the sheets being folded inwardly towards the same face or surface of the central portions;

Figure 15 is a fragmentary view in side elevation and showing the feed roller positioned so as to effect formation of parallel folds, one end 35 portion of the sheet being folded towards one face of the central portion, and the other end portion being folded towards the other face of said central portion; and

Figures 16, 17 and 18 are diagrammatic views 40 illustrating the operation of the mechanism as set up in Figure 15.

The preferred embodiment of the invention shown in the drawings for the purposes of illustration includes a frame A which conveniently 45 may comprise side members 1 and 2, bottom cross pieces 3 and 4, top cross pieces 5 and 6 and an elevated sheet-receiving platform 7, which latter is preferably provided with receiving skids 8. In the form shown the frame includes also bearing bracket members 9 and 10 connected to the side 50 2 and joined at their top ends by a cross piece 11, and bearing bracket members 12 and 13 connected to the side 1 and joined at their top ends 55 by a crosspiece 14. An upright supporting mem-

ber 15 is mounted on the cross piece 5 and serves to support a sheet guide table 16, the purpose of which will be described later. The parts thus far described may be, and in the form shown are, secured together so as to be relatively immovable and thus to constitute a rigid frame.

Folding mechanism generally designated B includes two parallel and peripherally engaged folding rolls 17 and 18 mounted with their axes in a horizontal plane, the roll 17 having stub shafts or trunnions 19 journaled in blocks 20 mounted for sliding horizontal movements in slots 21 in the bracket members 9 and 12; and the roll 18 having stub shafts or trunnions 22 journaled 10 in the brackets 10 and 13. The roll 17 is urged into engagement with the roll 18 by means of springs 23 interposed between the trunnions 19 and 22. A third roll 24 is mounted above and in peripheral engagement with the roll 18 by means 15 of trunnions 25 journaled in blocks 26 mounted for vertical sliding movements in slots 27 in the brackets 10 and 13. Springs 28 interposed between the trunnions 25 and the trunnions 22 of the roll 18 urge the roll 24 into engagement with 20 the roll 18. The rolls may be formed of, or surfaced with, a suitable yielding material such as cork, rubber or the like.

Means, in the form shown a support 29, is provided under the rolls 17 and 18 for holding a pile 30 of sheets to be folded, the support being urged upwardly towards the rolls by means of leaf springs 31 secured to the cross pieces 3 and 4 and engaging the bottom of the support. A cord 32 connected to the support as at 33 and to the frame as at 34 and 35 limits endwise movement of the support without danger of binding which might be caused by fixed guides. Upward movement of the support and pile of sheets is limited by engagement of the latter with a feed roller 36 and one or the other of the frame top cross pieces 5 and 6 depending upon which of two positions the feed roller is mounted in. A sheet-positioning abutment 29^a is adapted to be secured to the platform 29 in adjusted position by means 40 of a bolt 29^b passing through the abutment and a slot 29^c in the platform and having a wing nut 29^d on its lower end. By adjusting the position of the abutment 29^a it is possible to position the sheets in such relation to the folding rolls as to cause the folds to be formed at the desired part 45 of the sheet. Latch elements 29^e and 29^f on the frame and platform are adapted to cooperate for maintaining the platform in retracted position to facilitate positioning of the sheets. A hump 50 55 29^g extending across the platform 29 deforms the sheets upwardly to facilitate formation of the commencement of a fold by buckling.

The feed roller 36 is secured to a shaft 37 by means of set screws 38, the shaft being adapted to 60 be journaled in bearings 39 at the left of the roll 17, or in bearings 40—40 at the right of the roll 18, as viewed in Figures 1 and 2. The arrangement is such that when the set screws 38 are loosened the shaft 37 may be withdrawn from one 65 pair of bearings and the feed roller and shaft assembly then set up for rotation in the other set of bearings, the purpose of shifting the feed roller assembly being explained hereinafter. The feed roller may be formed of or surfaced with material such as rubber, having a tendency to grip the sheets frictionally and preferably the periphery of the roller is serrated in order to provide for a more complete gripping action and more effective feeding.

75 Take-off rollers 41 mounted on a shaft 42 jour-

nalled in bearings 43 are disposed in position to receive folded sheets emerging from between the rolls 18 and 24, and to move the folded sheets on to the skids 8. The take-off rollers also may be serrated in order to more surely grip and feed the sheets.

Preferably the folding rolls 17, 18 and 24, the feed roller 36 and the take-off rollers 41 are driven by common operating means such as a crank 44 secured to a gear 45 mounted for rotation on a 10 stub shaft 46. Motion of the crank and gear 45 is transmitted to the folding rolls 17, 18 and 24 through the medium of a gear 47 secured to the roll 18 and meshing with the gear 45. Belts 48 and 49 pass around pulleys 50 and 51 secured to 15 the crank 44 and respectively around a pulley 52 secured to the shaft 42 of the take-off rollers 41 and a pulley 53 loosely mounted on the shaft 37 of the feed roller 36. The pulley 53 is mounted loosely on the shaft 37 in order to provide a free 20 wheeling or over running drive for the feed roller, thus permitting sheets which are gripped by the folding rolls 17 and 18 to be withdrawn from under the feed roller 36 without the latter's exerting a drag on the sheets. The drive from the 25 pulley to the feed roller shaft is effected by means of a pin 54 fixed to the pulley and a pin 55 fixed to the shaft and adapted to be engaged by the pin 54 when the pulley is rotated.

In operation, the feed roller 36 rotates in a 30 clockwise direction as viewed in Figure 2 and buckles the top sheet 30^a so as to form the commencement of a fold at 30^b and to raise the buckled portion into contact with the rolls 17 and 18 which are rotating in the direction of the 35 arrows in Figure 2. The sheet is then passed between the rolls 17 and 18 and the fold emerges vertically as shown in Figure 7. In some cases it is desirable to form only one fold in the sheet and for accomplishing this I provide guide means 40 preferably comprising a sheet metal member 56 secured to the upright supporting member 15 by means of a bolt 57 and wing nut 58 and having a guide portion 59 disposed above the line of engagement of the rolls 17 and 18 and curved in 45 a manner to deflect the folded sheet between the rolls 18 and 24 which will act merely as feeding or discharging rollers delivering the once-folded sheet to the take-off rollers 41 which, in turn, deliver the sheet to the skids 8 on the platform 7. 50 Retaining rods 60 adjustably mounted in slots 61 in the platform 7 prevent the folded sheets from falling off the end of the platform.

A weight 60^a may be placed on top of the folded sheets to prevent them from bulging and stacking 55 up too high.

In other cases it may be desired to form two parallel folds in the sheets. This requires that the sheet be routed through the folding rolls differently; and in accordance with my invention 60 the change in routing is effected by positioning a different guide portion 62 of the member 56 in the path of sheets emerging from the rolls 17 and 18. The guide portion 62 is curved, as shown in Figures 12, 13 and 14 so as to deflect the emerging 65 once-folded sheet away from the rolls 18 and 24, and under the guide member 56 until the formed fold engages an abutment 63 between the guide member 56 and the guide table 16 after which a second fold forms at 30^c and the twice folded 70 sheet passes between the rolls 18 and 24 as shown in Figure 13. Thus, through the provision of interchangeable guide means, the sheets may be routed so as to form either a single fold or two parallel folds. For convenience and simplicity 75

the guide portions 59 and 62 are both formed on the single element 56 which need only be reversed in order to provide for the required change in routing of the sheet. The abutment 63 is clamped in adjusted position by means of the wing nut 58, being adjustable towards or away from the rolls 18 and 24 for varying the position of the second fold 30^c.

Apparatus in accordance with my invention 10 is adapted to be adjusted to adapt it for the formation of different kinds of folds, depending upon the size of the sheet, the nature of printed matter thereon, or other factors. In order that the cooperation of the various parts may be 15 more fully understood, complete cycles of operation will be described for different adjusted positions.

When it is desired to form a single fold in each of the sheets, as by folding the sheets 20 transversely in half, the apparatus will be set up as shown in Figures 1, 2, 3, 4 and 6 to 11 inclusive, the feed roller 36 being mounted to the right of the folding roll 18 and the guide portion 59 being disposed above the line of contact 25 of the folding rolls 17 and 18. The springs 31 will urge the platform 29 upwardly, movement of the latter and the pile 30 of sheets being limited by engagement of the latter with the cross piece 5 and the feed roller 36 so as to be held 30 out of contact with the folding rolls 17 and 18.

Before the crank 44 is turned in order to start 35 operation, the pin 55 on the loose pulley 53 and the pin 54 on the feed roller shaft 37 will be in the positions shown in Fig. 6. When the 40 crank 44 is turned in a counter clockwise direction the pulley 53, folding roll 18 and take-off rollers 41 will be driven in a clockwise direction. The pin 55 on the pulley 53 being in engagement with the pin 54 on the shaft 37 will drive the 45 feed roller causing the latter to feed the right hand end portion of the top sheet 30^a toward the left so as to buckle the sheet bringing it into contact with the rollers 17 and 18 by which the sheet will be grasped and a fold 30^b formed 50 as the sheet passes through the rolls. The position of the pins 54 and 55 at the time the fold 30^b is formed is shown in Figure 7. The rolls 17 and 18 being moved at a rate to feed the sheet faster than the feed roller 36 will draw the sheet 55 along under the feed roll causing the latter to run in advance of the pulley 53, there being no drag exerted by the feed roller. The positions of the parts just as the fold 30^b emerges from between the rolls 17 and 18 and just before the 60 right hand end of the top sheet is withdrawn from under the feed roller are shown in Figure 8, wherein the feed roller 36 has run about 90° in advance of the pulley 53. The fold 30^b upon emerging from between the rolls 17 and 18 will 65 engage the guide portion 59 which will deflect it between the rolls 18 and 24 as indicated in Figures 8 and 9. By the time the fold 30^b has actually entered between the rolls 18 and 24 the top sheet will have been withdrawn from under the feed roller 36 which will then contact the next lower sheet. The sheet 30^a will then 70 be fed through the feed rolls and onto the take-off rollers 41. While the sheet is being fed from the position shown in Figure 9 to that shown in Figure 10 the feed roller will remain stationary because of the lead of the pin 54 over the pin 55. Thus the sheet next below the sheet 30^a will not be fed to the folding rollers until the top sheet 30^a is well on its way through the folding 75 rolls. By the time the sheet 30^a reaches the po-

sition shown in Figure 10 the pin 55 on the pulley 53 will have moved up into engagement with the pin 54 on the feed roller shaft and rotation of the feed roller will be resumed causing the sheet next below the sheet 30^a to be buckled and fed to the rolls 17 and 18 as shown in Figure 11. By virtue of the free wheeling drive of the feed roller and the timing of the various rolls and rollers the sheets will be caused to follow each other closely through the folding rolls without 10 danger of being folded together. As the sheets emerge from between the rolls 18 and 24 they will be delivered to the take-off rollers 41 which will move them toward the right and dispose them one under the other on the skids 8. 15

When it is desired to form two parallel folds in a sheet, both end portions of the sheet being folded inwardly toward the same surface or face of the central portion, the mechanism will be set up as shown in Figures 1, 2, 3 and 4 with the 20 exception that the guide portion 62 of the guide member 56 will be disposed over the line of contact of the rolls 17 and 18 and the pile 30 will be shifted toward the right so as to bring the line of the first fold to be formed approximately 25 under the line of contact of the rolls 17 and 18. Figures 12, 13 and 14 show diagrammatically the path of the sheet through the folding rolls when the machine is set up in this manner. The operation of the feed roller in timed relation 30 to the folding rolls will be similar to that described above. The top sheet 30^a will be buckled as previously described, but the line of buckling and hence the line of the first fold will be disposed adjacent the left hand end of the sheet. 35 The sheet with the first fold therein will then pass between the rolls 17 and 18 and will engage the guide portion 62 which will deflect the fold 30^b toward the left into engagement with the abutment 63 as shown in Figure 13. Further 40 rotation of the folding rolls would cause a second fold 30^c to be formed as shown in Figure 13. The rolls 18 and 24 will then grip the twice folded sheet and feed it onto the take-off rollers 41, Figure 14 showing the twice folded sheet passing 45 between the rolls 18 and 24. It will be understood that in some cases it may be desired to fold the sheets in half by means of a single fold as described in connection with the diagrammatic Figures 6 to 11, inclusive, and then to reset the 50 apparatus and run the sheets through the rolls with the first formed fold transverse to the roll axes so as to form two folds transverse to the first halving fold.

The folds formed in the manner described with 55 reference to Figures 12, 13 and 14 are suitable for folding ordinary business letters or the like for insertion in closed opaque envelopes, all of the printed matter being folded in so as not to be visible on the folded sheet. If, however, it is 60 desired that one of the three sections of the sheet formed by the folds be on the outside of the folded sheet, for example, to display the address at the top of the letter through the window of a window envelope, the machine will be set up as 65 shown in Figure 15 and the passage of the sheets through the folding rolls will be as shown diagrammatically in Figures 16, 17 and 18. With the machine thus set up the feed roller 36 will be disposed toward the left of the folding roll 17, the feed roller shaft 37 being journaled in the 70 bearings 39 and the belt will be uncrossed so as to drive the feed roller in a counter clockwise direction. The abutment 29^a would be positioned to the right of the folding rolls so as to locate the 75

pile of sheets with their right hand end portions disposed under the rolls 17 and 18. When the crank 44 is rotated in a counter clockwise direction the feed roller 36 will buckle the top sheet 5 30^a and feed it inwardly toward the right, the buckled portion being gripped by the folding rolls 17 and 18 and fed upwardly therethrough as shown in Figure 16. The first fold 30^b will engage the guide portion 62 which will deflect it 10 toward the left into engagement with the abutment 63 at which time the rolls 18 and 24 will grip the trailing portion of the sheet and form a second fold 30^c and will feed the twice folded sheet onto the take-off rolls. It will be clear 15 from an inspection of Figures 17 and 18 that in the formation of the first fold 30^b the adjacent end portion of the sheet will be folded against one face of the central portion whereas in the formation of the second fold 30^c the end portion 20 adjacent this fold will be folded against the opposite face of the central portion of the sheet. By folding the sheet in this manner the address can be exposed on one end portion and at the same time all other printed matter folded in so as 25 not to be exposed.

The position on the sheets at which the first fold is formed is controlled by the initial positioning of the sheets on the platform 28 and the positioning on the sheets at which the second fold is formed may be varied by shifting the adjustable abutment 63 towards or from the rolls 18 and 24.

From the foregoing it is apparent that because of the novel arrangement and relative disposition 35 of the parts comprising my improved sheet folding mechanism, and the adaptability of the parts to selective arrangement, I am able with a single compact mechanism to fold sheets in any of the different ways usually required. Although the 40 mechanism is of simple and inexpensive construction it has been found to function rapidly and with reliability, the over running drive for the feed roller preventing the folding of two or more sheets together.

45 The mechanism disclosed herein is a practical and the at present preferred embodiment of the invention but changes may be made in the specific construction and relative arrangement of the parts without departing from the invention as 50 defined in the claims.

I claim:

1. In sheet folding mechanism, the combination of an element for forming folds and feeding a folded sheet; a roller for effecting commencement 55 of a fold in a sheet and delivering said sheet to said fold-forming and feeding element; a common driving means for said fold-forming and feeding element and said roller; and driving connections between said driving means and said 60 roller including an over running drive device, said driving connections being such as at all times to provide uninterrupted driving connection except for said over running drive device.

2. In sheet folding mechanism, the combination 65 of a fold-forming and feeding element; means for supporting a pile of sheets; a roller in constant contact with said pile of sheets and adapted to effect commencement of a fold in a sheet and to deliver said sheet to said fold-forming and feeding element; driving means; and 70 drive connections between said driving means and said roller including a shaft connected to the roller, a wheel mounted for rotation rela-

tively and coaxially with respect to said shaft, a single abutment on said shaft, and a single cooperating abutment on said wheel adapted to engage said shaft abutment to effect driving connection between the wheel and the shaft. 5

3. In sheet folding mechanism, the combination 10 of a fold-forming and feeding element; means for supporting a pile of sheets; a roller in constant contact with said pile of sheets and adapted to effect commencement of a fold in a sheet and to deliver said sheet to said fold-forming and feeding element; means for driving said fold-forming and feeding element and said roller at such rates that the former feeds the sheet faster than the latter; and driving connections between 15 said driving means and said roller including an over running drive device, said driving connections being such as at all times to provide uninterrupted driving connection except for said over running drive device. 20

4. In sheet folding mechanism, the combination 25 of a plurality of fold-forming rollers; a feed roller adapted to start a fold in a sheet and deliver said sheet to the fold-forming rollers; driving means for all of said rollers; and driving 30 connections between said driving means and said roller including an over running drive device, said driving connections being such as at all times to provide uninterrupted driving connection except for said over running drive device. 35

5. In sheet folding mechanism, the combination 40 of fold-forming rollers, means for supporting a pile of sheets, a feed roller in constant contact with said pile and adapted to deliver individual sheets to said fold-forming rollers; driving means for all said rollers adapted to drive them at such relative speeds that the fold-forming rollers move a sheet more rapidly than the feed roller; and driving connections between said driving 45 means and said roller including an over running drive device, said driving connections being such as at all times to provide uninterrupted driving connection except for said over running drive device, the drive being so timed that when a sheet is in engagement with the fold-forming rollers it will cause the feed roller to free-wheel until the sheet has been withdrawn from contact with said feed roller, the latter then immediately engaging the next sheet of the pile. 50

6. In sheet folding mechanism, the combination 55 of folding rolls adapted to form two parallel folds in a sheet; means for holding a pile of sheets adjacent to but out of contact with said rolls and with two opposite edges of the pile disposed parallel to the axes of the folding rollers and respectively on opposite sides of the axes; a feed roller adapted to engage the sheet of said pile nearest said folding rolls and to deliver an intermediate portion of said sheet to said folding rolls; and means for selectively mounting said feed roller in 60 either of two positions so as to engage said sheet and feed it selectively from either of said two opposite pile edges. 65

7. In sheet folding mechanism, the combination 70 of folding rolls adapted to form two parallel folds in a sheet; means for holding a pile of sheets adjacent to but out of contact with said rolls and with two opposite edges of the pile disposed parallel to the axes of the folding rollers; a feed roller adapted to engage the sheet of said pile nearest said folding rolls and to deliver an intermediate portion of said sheet to said folding rolls; and separate bearings for said feed roller located on opposite sides of said folding rolls, the feed roller being adapted to be mounted for rotation in either 75

of said separate bearings, and thus being adapted to feed sheets towards said folding rollers from either of said opposite pile edges.

8. In sheet folding mechanism, the combination of folding rolls adapted to form two parallel folds in a sheet; means for holding a pile of sheets adjacent to but out of contact with said rolls and with two opposite edges of the pile disposed parallel to the axes of the folding rollers; a feed roller adapted to engage the sheet of said pile nearest said folding rolls and to deliver an intermediate portion of said sheet to said folding rolls; separate bearings for said feed roller located on opposite sides of said folding rolls, the feed roller being adapted to be mounted for rotation in either of said separate bearings, and thus being adapted to feed sheets towards said folding rollers from either of said opposite pile edges; and means for driving said folding rolls and said feed roller including a drive connection adapted to drive the feed roller clockwise or counter-clockwise depending upon which of said bearings it is mounted in.

9. In sheet folding mechanism the combination of two folding rolls having peripheral engagement with each other and having parallel axes substantially in a horizontal plane; a third roll disposed above and peripherally contacting one of said first two rolls; a sheet support mounted under said first two rolls; means for urging said support and a pile of sheets supported thereon upwards towards said first two rolls; and means for engaging the top sheet of the pile and limiting movement of the support and the pile so as to prevent the pile's being pressed against said first two rolls, said means including a feed roller which when rotated buckles the top sheet and moves it into engagement with said first two rolls.

10. In sheet folding mechanism the combination of two folding rolls having peripheral engagement with each other and having parallel axes substantially in a horizontal plane; a third roll disposed above and peripherally contacting one of said first two rolls; a sheet support mounted under said first two rolls; means for urging said support and a pile of sheets supported thereon upwards towards said first two rolls; and means for driving said rollers; means for guiding a sheet passed between said first two rollers between the third roll and the roll with which it peripherally contacts; a take-off roller disposed in position to receive sheets discharged from between said last mentioned rolls and to move said sheets away from said rolls; and means for driving said take-off roller.

11. In sheet folding mechanism the combination of two folding rolls having peripheral engagement with each other and having parallel axes substantially in a horizontal plane; a third roll disposed above and peripherally contacting one of said first two rolls; a sheet support mounted under said first two rolls; means for urging said support and a pile of sheets supported thereon upwards towards said first two rolls; and means for driving said rollers; means for guiding a sheet passed between said first two rollers between the third roll and the roll with which it peripherally contacts; a take-off roller disposed in position to receive sheets discharged from between said last mentioned rolls and to move said sheets away from said rolls; and means for driving said take-off roller.

12. In sheet folding mechanism the combination of two folding rolls having peripheral engagement with each other and having parallel axes substantially in a horizontal plane; a sheet support mounted under said rolls; means for urging said support and a pile of sheets supported thereon upwards towards said rolls; and means for engaging the top sheet of the pile and limiting movement of the support and the pile so as to prevent the pile's being pressed against said rolls, said means including a fixed element on one side of said rolls, and a feed roller on the opposite side of said rolls and which when rotated buckles the top sheet and moves it into engagement with said rolls.

ROBERT C. FLYNT.
